UNITED STATES PATENT OFFICE.

DAYTON BALL, OF ALBANY, NEW YORK.

DESIGN FOR A PAPER-WEIGHT.

SPECIFICATION forming part of Design No. 18,064, dated February 21, 1888.

Application filed January 18, 1888. Serial No. 261,146. Term of patent 7 years.

To all whom it may concern:

Be it known that I, DAYTON BALL, of the city and county of Albany, in the State of New York, have invented and produced a new and original Design for Paper-Weights, of which the following is a full, clear, and exact description, reference being had to the accompanying photographic illustration, which forms part of this specification, and in which is shown a front elevation of my paper-weight.

The special feature of my new design for a paper-weight consists of a panel or block which has on its upper face a bas-relief of a shoe-last in profile.

As represented in the illustration, A indicates the panel or block of my paper-weight of rectangular form. The ornamentation of said panel consists of a bas-relief, B, representing a shoe-last in profile. The upper outline of said bas-relief is defined by a concave line, 1, that is joined at the apex 2 to an ogee

line, 3. The lower outline is defined by an ogee line, 4, which merges into a convex line, 5, and the rearmost outline is defined by a convex line, 6, which connects with the concave line 1 and convex line 5, said rearmost outline being arranged in an approximately erect position. An incised concave line, 7, which inclines downward and forward from the concave line 1, joins a like line, 8, which connects with the ogee line 3.

What I claim as new, and desire to secure by Letters Patent, is—

In a design for a paper-weight herein shown and described, the ornamentation of the panel A, consisting of a bas-relief, B, of a shoe-last, as herein specified.

DAYTON BALL.
